UNITED STATES PATENT OFFICE.

ANDREW L. HILL, OF CHICAGO, ILLINOIS.

HAME-TUG.

SPECIFICATION forming part of Letters Patent No. 322,934, dated July 28, 1885.

Application filed December 13, 1884. (No model.)

To all whom it may concern:

Be it known that I, ANDREW L. HILL, a resident of the city of Chicago, county of Cook, and State of Illinois, have invented certain new and useful Improvements in Hame-Tugs, 5 of which the following is a specification.

My invention consists of certain details of construction and combinations of parts, as hereinafter set forth and claimed.

10 In the drawings accompanying and forming a part of this specification, Figure 1 represents my device in perspective. Fig. 2 shows the construction of my box-loop. Fig. 3 is an edge view of my draft-iron. Fig. 4 is a plan 15 or face view of Fig. 3. Fig. 5 is a plan or face view of my shield, and Fig. 6 is a perspective view of a detachable end of the draft-iron.

a represents the shield or fender.

20 *a' a'* are elongated openings in the upper or outer portion of the fender.

b is the customary opening through the end of the fender.

25 *c* is the box-loop provided with outwardly-extending flanges *c' c'*.

d is an opening in the upper or outer portion of the fender to permit the draft-iron to protrude therefrom.

30 *e e* represent a bifurcated hook on the end of the draft-iron.

f represents the draft-iron provided with the customary curved extension *f'* and detachable plate *g*.

35 *h* is a slot in the draft-iron, which receives the pin *g'* on plate *g*.

i is a rivet-hole in the draft-iron.

The fender is composed of two pieces of leather stitched together at their edges.

The box-loop is provided with flanges that project outward between the two layers of 40 fender in such a manner as to be secured by the same seam that completes the fender.

The part *g* is detachable from draft-iron *f*.

The fender is first formed with the box-loop 45 stitched in, after which the draft-iron *f* is inserted from the front and plate *g* slid into position through opening *d*.

This completes the tug ready for sale to the dealer, who can complete the same by riveting *f'* to the hame in the customary manner 50 by placing a suitable buckle in hooks *e e*, and by riveting through hole *i*.

I claim as new and desire to secure by Letters Patent—

1. The combination, in a hame-tug, of draft- 55 iron *f*, provided with slot *h*, and plate *g*, provided with hooks *e e* and pin *g'*, as and for the purpose set forth.

2. The combination of fender *a*, provided with openings *a' a'* and *d*, box-loop *c*, provided 60 with outwardly-extending flanges *c' c'*, and draft-iron *f f' g e e*, as and for the purpose set forth.

ANDREW L. HILL.
